UNITED STATES PATENT OFFICE.

MARK BRAYMES, OF PHILADELPHIA, PENNSYLVANIA.

RECLINING-CHAIR.

SPECIFICATION forming part of Letters Patent No. 690,012, dated December 31, 1901.

Application filed April 17, 1901. Serial No. 56,308. (No model.)

To all whom it may concern:

Be it known that I, MARK BRAYMES, a citizen of the United States, residing at Philadelphia, in the county of Philadelphia and 5 State of Pennsylvania, have invented a new and useful Reclining-Chair, of which the following is a specification.

My invention relates to improvements in reclining-chairs in which the inclination of 10 the back is changeable; and the objects of my improvements are, first, to provide an arrangement of parts whereby the desirable inclination of the back may be obtained by the occupant of the chair while remaining in a 15 sitting posture, and, second, to reduce the cost of manufacturing reclining-chairs and at the same time to improve their appearance. I attain these and other desirable objects by the means described in the following specification and pointed out in the accompanying claim.

In the drawings, Figure 1 is a side view and part section of the reclining-chair. Fig. 2 is a plan view of the adjustment-rack. Fig. 3 25 is a side view of the same. Fig. 4 is a detailed view in section on line xx of Fig. 5 and showing the rack engaged to the pin, and Fig. 5 is a plan view of Fig. 4.

Similar numbers refer to similar parts 30 throughout the several views.

1 is the frame forming the movable back of the reclining-chair. It is secured to the seat 2 by means of hinges, formed by a hook 3, attached to the lowest part of the movable back 35 1, and which engage into eyelets 4, attached to the rear part of the seat 2.

The desired inclination of the movable back 1 is obtained by means of an adjustment-rack 5. This adjustment-rack can be made of several 40 pieces and of different shapes; but in my invention to reduce the cost of manufacturing I make the adjustment-rack in one piece, using for that purpose a rod of any suitable metal. This rod is bent at right angles, so as to form the three sides of a rectangle. The longest side 5, forming the rear of the adjustment-rack, is held to the movable back by means of metal straps 10, which are held fast to their place. These straps 45 50 form the pivoting-point of the rack and allow it to freely turn up and down. The short sides 6 of the adjustment-rack are brought

forward on each side of the movable back and have their extremity 7 flattened and bent downward to the desired curve. Teeth 8 are 55 cut into the inside edge of the curve. This curve insures a proper working of the adjustment-rack by preventing bending or forced contact of the sides 6 with the arms 11. A slot 9 is cut into the arms 11. The arms remain in a fixed position, being attached to the seat-frame 2. The toothed curve of the adjustment-rack enters freely into the slot 9 and engages a pin 12, which is driven through the arm and across the slot. To protect the 60 edges of the slot, I place upon the arms a metal plate 18, having an opening cut out of the same size as the slot.

To change the inclination of the movable back, all that is required is to slightly pull 70 forward the adjustment-rack, so as to disengage its tooth from the pin 12, lift the adjustment-rack if more inclination is desired or lower the adjustment-rack if a more vertical position of the movable back is sought 75 for, and then hook the toothed portion of the curve on the pin 12. It is seen at once that such change in the inclination of the movable back can be made while the person using the chair remains in a sitting posture. 80

The frames 1, 2, and 11, forming, respectively, the back, seat, and arms of the reclining-chair, can be finished in any convenient style. In the present instance, and to obviate the necessity of using expensive wood, 85 the exposed portions of the back, seat, and arm are upholstered with suitable material.

The seat-frame 1 can be made of one solid piece; but in the present instance I prefer to make it in the shape of a hollow square filled 90 and upholstered in any convenient manner. Each side of the seat-frame has a rectangular cross-section, the longest side being laid horizontal. The lower edge of the seat-frame being of the same size as the metal frame 95 would have a tendency to slip off whenever any one should use the chair. To prevent this, I cut off a strip all around the lower edge of the seat-frame and at a suitable angle, so that the seat will engage in the metal 100 frame, the depth of the engagement being proportional to the amount of material removed from the lower edge of the seat-frame.

The metal frame 13 and the legs 14 are

made of any convenient metal in one or more pieces. In the present instance, however, and for the purpose of improving the general appearance of the chair and to reduce its manufacturing cost I make the frame and legs of cast-iron, the legs being attached to the frame by means of bolts and nuts, all the exposed metal parts being nickel-plated.

Changes may be made in the form, proportions, and minor details of construction without departing from the spirit of this invention.

Having now described my invention, what I claim, and desire to secure by Letters Patent, is—

The combination with a removable seat-frame having arms, of hollow uprights connecting the rear end of each of the said arms to the removable seat-frame; of a movable

back-frame hinged to the removable seat-frame; of slots in the arms registering with the hollow uprights; of an adjustment-rack pivoted to the movable back-frame and adapted to enter the slots in the arms and the hollow uprights; of a locking device placed inside of the hollow uprights and adapted to hold in place the adjustment-rack; of a metal frame and legs on which to rest and engage the removable seat-frame; all substantially as set forth and for the purpose specified.

In testimony whereof I have signed my name to this application in the presence of two subscribing witnesses.

MARK BRAYMES.
